DESIGN FOR A CAP OR THE LIKE

Tobias Noped, Brooklyn, N. Y., assignor to Noped M'fg. Co., a copartnership composed of Tobias Noped and Gertrude Noped, New York, N. Y.

Application May 21, 1948, Serial No. 146,504

Term of patent 14 years

(Cl. D3—13)

To all whom it may concern:

Be it known that I, Tobias Noped, a citizen of the United States of America, residing at Brooklyn, in the county of Kings, city and State of New York, have invented a new, original, and ornamental Design for a Cap or the like, of which the following is a specification, reference being had to the accompanying drawing, forming part thereof.

In the drawing:

Fig. 1 is a front perspective view of a cap or the like, showing my new design;

Fig. 2 is a side elevational view thereof, the opposite side of the cap being identical with the side shown.

I claim:

The ornamental design for a cap or the like, substantially as shown and described.

TOBIAS NOPED.
